Electric Corporation, East Pittsburgh, Pa., a
corporation of Pennsylvania

Application October 8, 1942, Serial No. 461,336

8 Claims. (Cl. 178—44)

1

In its broader aspect, this invention relates to receiving and transmitting energy in the form of electro-magnetic waves and more specifically it relates to a novel switch which is connected between the transmitter and receiver and serves the purpose of protecting the receiver during the transmission pulse.

Use of reflection of radio waves for various purposes, such as determination of altitude of an airplane to ground, for locating one airplane from another or from a fixed situation, and for other purposes, is an acknowledged fact. The wave is generated, passed to the antenna and into space, reflects from the object addressed, returns to the antenna and thence to the receiver. A switch of automatic character has to be provided to keep the projected pulse from passing through the receiver at the time of projection but which will permit the reflected pulse to operate the receiver. Such a switch is now commonly referred to as a "TR box."

The present invention is directed primarily to an improved TR box capable of use with a wave guide. The term "wave guide" is used to describe the means by which electro-magnetic energy is propagated in hollow tubes from one place to another before its ultimate transmission into free space, if that is to be done. More specifically, a wave guide includes the provision of a dielectric, such as air within a channel, the wave guide extending from place to place and constituting a metallic boundary laterally engirdling the dielectric. The cross-sectional dimensions of the metallic boundary of the wave guide have a definite relation to the character of the wave transmitted thereby. Literature has employed and this description will correspondingly employ the letter *a* to designate the short dimension and letter *b* to designate the long dimension of the cross section of a rectangular wave guide. In the present specification selection of a particular mode is employed for simplicity, and by arbitrary choice herein that propagation of electro-magnetic energy is by means of the H_{01} wave. It is to be understood, however, that other modes may be used and other shapes and dimensions of wave guides may be employed.

The degree of delicacy of operation of the TR box is highly important as it is essential that the high power of the outgoing signal shall not paralyze or even filter through to the receiver, and yet it is imperative that the faintest of reflected signals shall pass through the switch to the receiver.

The present invention accordingly has for its primary object the provision of a switch or TR

2

box meeting the exacting requirements outlined above and with greater effectiveness than accomplished by devices of the prior art.

More specifically, an object of the invention is to provide a TR box with a cartridge type electrode assembly.

Another object of the invention is to localize the necessary evacuated region, and to require partial vacuum only within the cartridge.

10 A further object of the invention is to provide a tunable TR box with the electrodes and cartridge envelope maintaining an undisturbed relationship and with the partial vacuum undisturbed.

15 A still further object of the invention is to utilize moving parts for tuning purposes entirely outside of the cartridge.

Again, an object of the invention is to provide a cartridge construction which is readily removable and replaceable and necessitates minimum material and labor loss represented by the substitution.

20 Another object is to provide for proper orientation of the cartridge in the resonator and also to establish desired resonance mode.

Still further objects of the invention will appear 25 as the description progresses, both by direct recitation thereof and by implication from the context.

Referring to the accompanying drawings in which like numerals of reference indicate similar parts throughout the several views:

Figure 1 is a sectional view longitudinally through a TR box and associated wave guide, as on line I—I of Figure 2;

Figure 2 is a sectional view longitudinally of the 35 wave guide and transversely of the TR box, as upon line II—II of Figure 1;

Figure 3 is an elevation of the cartridge structure utilized in our improved TR box;

Figure 4 is a longitudinal sectional view of a 40 modified construction of cartridge;

Figure 5 is an elevation of the TR box or switch in its associated relationship with transmitting and receiving apparatus;

Figure 6 is a sectional view similar to Figure 1 45 showing a modified choke construction; and

Figure 7 is a cross section on line VII—VII of Figure 6.

In the specific embodiment of the invention 50 illustrated in said drawings, reference is first made to Figure 5 wherein is illustrated the general assembly of apparatus comprising a wave generator 10 productive of high pulse energy of desired frequency promulgated as H_{01} waves longitudinally of a wave guide 11 preferably of rectangular cross section. Such waves may be di-

rectionally transmitted into free space directly from the wave guide or through the agency of an antenna, such as a horn, or otherwise. Preferably the waves are sent forth from a parabolic device, which for brevity and ease of reference will be termed an antenna 12 which can be moved about for directing the wave path or beam in a desired direction and toward an object. The invention is preferably used in conjunction with ultra-high frequency radio waves, an advantage of which is the property of straight-forward projection and reflection in substantially the same manner as light waves. Accordingly, the projected wave energy directed toward some object, such as an airplane, reflects therefrom and on its return course between pulses is intercepted by the antenna 12 which concentrates the wave to re-enter wave guide 11 and travel therein and through a branch wave guide 13 to a receiver 14 which is then excited by the returned wave. The generator is placed at a specified distance from the junction of wave guides 11 and 13 so as to present such an impedance at the junction (in the quiescent state) so as to divert the received energy toward the receiver in guide 13. Obviously the returned wave energy will be very weak as compared to the high power of the energy produced by the wave generator. The TR box 15 is interposed in branch wave guide 13 between the receiver and generator and between the receiver and the antenna to automatically prevent the high power energy from generator 10 during transmission from destroying or interfering with the receiver and yet permitting the receiver to be actuated in consequence of the relatively weak power of the returned signal between pulses.

The switch or TR box of the present invention preferably comprises a cylindrical body of metal 16 which is hollow and in part provides a resonator chamber 17 therein. The body 16 is provided with a fixed end wall 18 which is situated in the plane of the long dimension wall b of the branch wave guide 13, the said body 16 extending from said fixed end wall 18 of the wave guide, transversely through the hollow of the wave guide and out through the opposite long dimension wall b of said wave guide. Apertures, closed by windows 19 of material transparent to the wave energy are provided at parts of the resonator body within the wave guide and centered upon the center line of the wave guide. The windows are of suitable dielectric material, such as low loss glass and serve as means for passing the flow of wave energy in the guide through the resonator. Said windows are suitably dimensioned both as to diameter and thickness and with due consideration to their dielectric constant, to introduce a minimum of disturbance and still give sufficient coupling between the resonator chamber and the wave guide. These window apertures are shown circular, though they need not be, and concentric with a diameter of the resonator as well as with the center line of the wave guide. The windowed apertures are preferably as small as practicable for still obtaining desired energy transfer without undue lessening of the surface continuity of the resonator. The area of the windows to a considerable extent controls the coupling coefficient, detailed discussion of which is out of place here. Since neither the resonator nor the wave guide, in accordance with preferred construction, are evacuated, there is no need for the windows to be vacuum tight, and it is within the scope of the invention to omit the windows and leave the aper-

tures open. Coaxial with and within the cylindrical resonator body is situated, in use, the removable and replaceable cartridge 20 constituting a feature of the present invention. The cartridge comprises essentially a long tubular envelope 21 within which are situated cylindrical electrodes 22, 22 opposed endwise toward each other on a common axis and coaxial with the envelope. The outwardly directed ends of the electrodes are mounted upon lead-in wires 23, 23 of sufficient rigidity to maintain the electrodes in the position shown with a gap 24 between the inwardly directed ends, said ends preferably being somewhat pointed. The glass of the envelope 21 is sealed around the lead-in wires, the envelope is evacuated, refilled with ionizable gas if desired to appropriate pressure, and tubulation 25 for that purpose sealed off. The cartridge is mounted to be removable in its entirety and replaceable at will, and in use should be situated symmetrical with respect to the center line of the wave guide, that is, the centerline of the wave guide should be normal to and pass between the inwardly directed ends of the electrodes. The glass tube 20 is of adequate internal volume to maintain long life of operation.

Projecting outwardly from the fixed end 18 of the resonator body is an inverted cup 26 of cylindrical shape and having an outer end 27 from which projects a neck 28. Said neck is coaxial with the said cup which in turn is coaxially aligned with the cylindrical body portion 16. Said cup furthermore is provided with an axial bore for receiving one of the lead-in wires 23 of the cartridge. When the cartridge is adjusted to its desired position a set screw 29 projecting radially inward of the neck is employed for clamping the lead-in wire at such position. It will now be clear that insertion, removal, and replacement, as well as adjustment of the cartridge, may be readily effected.

The bottom wall 30 of the resonator, that is, the wall opposite from the fixed end wall 18, is made adjustable. For that and other purposes said bottom wall is made integral with a cylindrical section 31 coaxial with and spaced inwardly from the body portion 16, the hollow of this cylindrical section affording the necessary region for introduction of the cartridge to its desired position within the resonator. At the outer peripheral face of the said cylindrical section intermediate the ends thereof is a flange 32 the outer peripheral face whereof is screw threaded, as at 33, and is engaged with corresponding screw threads on the interior peripheral face of body portion 16. The outer end of the cylindrical section 31 is formed with a cap 34 thereon said cap having a rim portion 35 which overlies the outer peripheral wall of the body portion. Said cap constitutes a convenient finger hold by which the same may be manipulated and it will, therefore, be clear from the above that rotation of the cap will obtain a corresponding rotation of the cylindrical section and its threaded flange thereby advancing or retracting the movable end wall 30 depending upon direction of rotation. Movement of the adjustable end wall 30 is for purposes of tuning the resonator.

Electrical continuity is necessary between the adjustable wall 30 and the cylindrical wall of the resonator, but sliding contact at the periphery of the said end wall is highly objectionable. The construction employed accordingly spaces the periphery of the adjustable end wall slightly in-

ward from the surface of the body portion of the resonator, leaving a gap 36 thereat. From the peripheral edge of the adjustable wall next the said gap, a skirt 37 projects rearwardly from the resonator said skirt being cylindrical and having a depth equal to a quarter wave length in the medium involved, which in the present showing is air. The adjustable wall 30 and skirt 37 accordingly constitute a piston, opening away from the resonator and setting up a high impedance at the open end. In consequence of the quarter wave length depth, high impedance at one end results in low impedance at the other end so that there will be low impedance at said gap 36 which wave energy recognizes as equivalent to contact between the surfaces and, therefore, constitutes electrical continuity without actual contact. This construction is referred to herein and in the trade as a choke.

Electrical continuity between the adjustable wall 30 and its adjacent electrode 22 and between the fixed wall 18 and its adjacent electrode 22 is obtained by a choke in a manner similar to that above described with respect to the adjustable wall and resonator body. The construction of choke accordingly provides a metal ring 38 for the fixed wall 18 and a metal ring 39 for the adjustable wall 30 of the resonator, both said rings projecting outwardly from the resonator and having an inside diameter of appropriate size for permitting the cartridge to loosely pass therethrough. Ring 38 is likewise smaller than the cylindrical wall of cup 26 so there is an annular space therebetween. This space is filled with a glass or other dielectric ring 40 having the same loss tangent and real dielectric constant as the glass of the cartridge envelope. Similarly, ring 39 is spaced inwardly from cylindrical section 21 leaving an annular space therebetween which is filled with a glass or other dielectric ring 41 also having the same loss tangent and real dielectric constant as the glass of the cartridge envelope. Each metallic ring 38 and 39 has an axial depth equal to a quarter wave length in the medium employed, which in the present instance is glass. Observation is made at this time, that the wave length in a dielectric such as glass is materially shorter than in air, and in the present showing, length of the metallic rings 38 and 39 represents a single quarter wave length for the glass dielectric as compared with the depth of the piston wall or skirt 37 heretofore described which represents a single quarter wave length in air. As explained above, high impedance at an open end means there must be low impedance a quarter wave length distant where the rings are attached to their respective end walls, wherefore, for the wave energy involved, there is electrical continuity thus obtained between the said end walls and the adjacent electrodes at the ends adjacent to the resonator 17. It may be here added that all parts above described, except those specifically referred to as glass or dielectric, are of suitable metal such as brass, copper and the like, to be electrically conductive.

In performing its function as a TR box, the resonator is constructed and positioned with respect to the junction of the wave guides 11 and 13 so as to present such an impedance at the junction to provide electrical continuity through the guide 11 during transmission and prevent leakage of power above a safe value to the receiver and furthermore to provide a suitable impedance at the junction during the period of reception (generator quiescent) so that the received

energy can pass substantially unattenuated to the receiver. In greater detail this means that some spark mechanism is placed in the resonator which is ineffective during small signals or small pulses and allows the energy to pass through substantially unattenuated. On the other hand, however, during the time when the generator 10 is operating and/or a large pulse is received, the spark gap discharges, reducing the Q of the resonator, and blocks the large signal there, cutting down the transmission through the TR box to protective values. This discharge occurs during the high pulse because a very high electric gradient is set up between the spark gap electrodes properly positioned in the resonator. The use of such a spark gap in the cylindrical resonator containing the spark gap electrodes coaxial with its axis will not permit an easy computation of the resonant frequency of the system.

As it has been found that there is a time lag, infinitesimal though it may be, in the high fields becoming effective to break down the gap between electrodes 22, 22 it becomes definitely desirable to obtain greater promptness in this respect. Generally speaking for the moment, this objective is attained by utilizing an ionizable gaseous medium in the resonator and a keep-alive therein by which a gas ionization is maintained and thereby supplying the desired ionizing radiation across the gap. Consequently when resonant potential builds up across the gap the moment of breakdown of the gap is accelerated, thus reducing the time lag in operation. Accordingly, the resonator body is first evacuated after which approximately one millimeter (or more if desired) of an appropriate gas is admitted. Suitable gases for the purposes include hydrogen, nitrogen, with or without water-vapor, as well as other gases alone or in combination.

For keep-alive purposes, one of the electrodes is rendered emissive. As shown in Figures 1 to 3 the inner end of one electrode has a radio-active or gamma emission material thereon, such as radium, as indicated at 47.

Other forms of keep-alive electrode may be provided, and in Figure 4 is shown a construction wherein glow discharge is obtained by a structure utilizing external potential for the purpose. Some modification of the envelope is likewise involved. In this showing one electrode 22' differs from electrode 22 in that it is hollow or tubular and has therein a rod or wire 42 which is a continuation of its lead-in wire 23. This rod extends to the forward end of electrode 22' so as to be at the forward opening of the electrode but without making contact therewith. Rod 42 may be of electron emissive character, such as tungsten-oxide-barium, tungsten-barium, strontium-barium and the like. The envelope 21' next the tubular electrode 22' is sealed to a metallic tube 43 of substantially the same diameter and the electrode 22' is flanged as at 44 next its outer end so as to fit this metallic tube for support and centering thereby. The flange 44 may be secured in place within the tube by soldering as at 45. Beyond the flange the lead-in wire 23 is sealed within the metallic tube by a glass bead 46. Potential difference between the tubular electrode and the rod 42 may be applied through the metallic sleeve 43 and the lead-in wire 23.

In the foregoing description, it will be observed that an important feature is the provision of a quarter wavelength of coaxial lines by metallic rings 38, 39 in conjunction with the electrodes 22, to secure effective electrical connection through

the glass of envelope 21 at the desired place between the electrodes and the body of the resonant chamber 17. The structure thus far described has the advantage of overall limitations of length by use of relatively short chokes by virtue of the hollows of the chokes being filled with the dielectrics 40 and 41 with the dielectric the same, or having the same dielectric constant, as the glass or wall of envelope 21. The inclusion of glass as dielectric rings 39 and 40, however, introduces certain difficulties in fabrication, due to the nature of the material and the desirability of obtaining a snug fit thereof in its appointed place. It is accordingly deemed within the scope of the invention to utilize other dielectric than glass, and to vary the arrangement of the choke if found desirable. A modified construction in this respect is accordingly shown in Figures 6 and 7.

In connection with the construction shown in Figures 6 and 7, those parts which are identical with parts heretofore described are identified by the same reference numerals and repetition of description thereof is omitted. As to parts which are similar, the same reference characters with the addition of the letter "a" thereafter are applied and the following description will set forth the differences so far as deemed necessary.

Metallic rings 39a and 40a are provided in this modified construction of Figures 6 and 7, said rings having a quarter wavelength dimension axially thereof as in the previously described construction, but in this instance said rings do not provide hollow spaces to the next adjacent surrounding wall, but are solid from their inner openings to said surrounding wall.

Axially outward from each said ring 39a and 40a is a choke, each being constituted by a longitudinal cavity 48 having a quarter wavelength dimension in the axial direction, the wavelength dimension being referred to the dielectric of the cavity, in this instance, in air. Said cavity in each instance has a circular slot opening or gap 49 at the end next the metallic ring and inwardly toward the cartridge or envelope. (The effect of this choke is to introduce a high impedance at the gap 49 thereby forcing a low impedance at the far end therefrom of the metallic ring, namely at the end of the metallic ring next the resonator chamber.) Thus, both constructions obtain this desired low impedance across the gap and provide the effect of electrical continuity between the electrodes and the adjacent wall of the resonant chamber.

The constructions shown are accordingly both of cartridge types, namely, long and slender and representing a minimum of evacuated volume. The cartridge can be inserted at the resonant chamber of the TR box, which chamber no longer has to be of partial vacuum type construction as in the prior art. This is extremely important because of the precision of part fabrication required of the resonant chamber of the TR box and the resulting high cost and difficulty of fabrication if each TR box is made as a complete and evacuated integral unit. With a TR box of the present invention any failure of partial vacuum or of the discharge electrode characteristics can be readily repaired or altered by simply inserting a new cartridge. It furthermore may be pointed out that an outstanding feature of the device of the present invention is the ability to arbitrarily select gap width for optimum operation and this gap will then be independent of the wavelength-controlling mechanism. More specifically, it is to be noted that tuning by rotation of cap 35 does

not affect the gap 24 between the electrodes at all.

Since the various details of construction, as well as the precise relation and functioning of parts, are subject to variation and change without departing from the inventive concept or scope of the invention, it is intended that all matter contained in the specification or illustrated in the drawings, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

We claim:

1. A TR box comprising a non-evacuated enclosure forming a resonant chamber having a cylindrical side wall, and said side wall having window openings to the exterior of said chamber, and a cartridge structure insertable through said chamber, said cartridge structure comprising a partially evacuated envelope and electrodes separated by a gap within said partially evacuated envelope, said gap being substantially opposite said window openings.
2. A TR box comprising an enclosure forming a resonant chamber having opposed end walls provided with openings therethrough, a cartridge structure traversing said chamber past said opposed end walls and projecting through said openings, said cartridge having electrodes therein, and means next said openings outside said end walls for establishing electrical continuity between said end walls and electrodes while maintaining physical separation thereof.
3. A TR box comprising an enclosure forming a resonant chamber and having a cylindrical wall, a movable wall to said chamber for tuning to desired resonance, said movable wall being spaced from the said cylindrical wall, means for establishing electrical continuity across said space, and a cartridge structure having a dielectric envelope in part within said chamber and having electrodes therein separated from each other by a gap and adapted to destroy resonance in said resonant chamber, one of said electrodes being in part within said movable wall and the envelope being interposed in part therebetween, and means for establishing electrical continuity between one electrode and said movable wall through said dielectric of the envelope at the said part thereof interposed between said one electrode and movable wall.
4. A TR box comprising an enclosure forming a resonant chamber and having a cylindrical wall and end walls of which one is adjustable in an axial direction of the cylindrical wall, said movable wall being spaced from said cylindrical wall, means for establishing electrical continuity across said space, a cartridge structure having a dielectric envelope in part extending through said end walls and in part within said chamber and having electrodes therein separated from each other by a gap, said electrodes projecting in part through said end walls within the envelope and the envelope being in part interposed between said electrodes and said end walls, and means for establishing electrical continuity through said interposed part of the envelope between each said electrode and the said end wall through which each electrode projects.
5. A TR box comprising an enclosure forming a resonant chamber and having a cylindrical wall and end walls of which one is adjustable in an

axial direction of the cylindrical wall, an electrode cartridge supporting means projecting from the fixed end wall, and supporting and adjusting means projecting from the movable end wall, both of said end walls having openings axially therethrough for receiving an electrode cartridge inserted therethrough, both of said end walls having quarter wavelength rings next said openings projecting outwardly from the resonant chamber for establishing electrical continuity at said openings with electrodes situated therein.

6. A TR box comprising an enclosure forming a resonant chamber, a cartridge structure insertable through said resonant chamber, said cartridge structure having electrodes each passing through a different wall of said enclosure, and means for establishing electrical continuity through the cartridge structure from the electrodes to the respective walls of the resonant chamber through which said electrodes pass, said means constituting a choke for said electrodes whereby mode distribution is maintained in said chamber.

7. A TR box comprising an enclosure forming a resonant chamber, a cartridge structure insertable through said resonant chamber, said cartridge structure having electrodes each passing through a different wall of said enclosure, means

for establishing electrical continuity through the cartridge structure from the electrodes to the respective walls of the resonant chamber through which said electrodes pass, said means constituting a choke for said electrodes whereby mode distribution is maintained in said chamber, said choke comprising a metallic ring and a solid dielectric around said ring of a length equal to a quarter wavelength in the dielectric.

- 10 8. A TR box comprising an enclosure forming a resonant chamber, a cartridge structure insertable through said resonant chamber, said cartridge structure having electrodes each passing through a different wall of said enclosure, means for establishing electrical continuity through the cartridge structure from the electrodes to the respective walls of the resonant chamber through which said electrodes pass, said means constituting a choke for said electrodes whereby mode distribution is maintained in said chamber, said choke comprising a metallic ring having longitudinally therebeyond a circular gap toward the cartridge and providing a longitudinal cavity communicating with said gap and extending longitudinally away from the said ring with a length equal to a quarter wavelength in air.
